UNITED STATES PATENT OFFICE.

ISAAC HODGSON AND WILLIAM H. BROWN, OF INDIANAPOLIS, INDIANA.

IMPROVEMENT IN FIRE-PROOF FLOORS AND CEILINGS.

Specification forming part of Letters Patent No. 129,955, dated July 30, 1872; antedated July 29, 1872.

To all whom it may concern:

Be it known that we, ISAAC HODGSON and WILLIAM H. BROWN, of the city of Indianapolis, in the county of Marion and State of Indiana, have jointly invented certain new and useful Improvements in the Construction of Fire-Proof Floors and Ceilings, of which the following is a specification:

The invention claimed under this patent relates more particularly to certain improvements upon the invention for which Letters Patent No. 115,472 were granted to us jointly, and bear date May 30, 1871; and our said invention consists of a new method of and devices for securing the horizontal flanged grooved transverse plates or beams to flanged floor-beams, to which the perforated lath-suspenders are also secured; also, in the arrangement of the ceiling and metallic lathing upon iron suspenders beneath the flanged base of the floor-beams in connection with having the lower flanges of said beams passing through the lath-suspenders directly above a concrete bed formed upon and above said metallic laths and plastering; the object of the said improvements being to construct thoroughly fire-proof floors and ceilings without overloading the floor-beams, and to render the construction cheaper, and to afford protection to the lower flanges of the floor-beams from the action of fire, as will be more particularly hereinafter described.

In the accompanying drawing, Figure 1 represents a view in perspective from the under side of a portion of ceiling and flooring constructed according to our invention. Fig. 2 represents an enlarged section of the same taken transversely with the floor-beams, and showing more clearly the arrangement of and connection of the floor and ceiling with the flanges of said beams, and the manner of deadening the floor. Fig. 3 represents a cross-section, on an enlarged scale, of the transverse grooved plates or hollow beams to which the flooring is secured, and the manner of supporting the corrugated plates to and between said beams.

The following description will enable skilled artisans to make and apply our invention.

The iron floor-beams A are, in the example shown, flanged at top and bottom and arranged at suitable distances apart, and to the

upper flanges whereof the grooved transverse plates or beams B are attached so as to extend across the floor-beams at right angles thereto. They are rolled with flanges C in their cross-section and riveted together in pairs, with suitable washers, between and through which the rivet-bolts pass. The fastening of the plates B to the floor-beams is made by lugs M, which are so riveted to the under side of the flange of each plate B as to allow them to be turned upon their rivets and driven under the flanges of the floor-beam, as shown in Figs. 2 and 3. The corrugated plates G are supported upon the flanges C, to which they are firmly riveted between the transverse plates B, as shown in Fig. 3. The flooring F is supported upon the upper edges of the grooved plates B and locked thereto by means of iron dogs E, as shown in Figs. 2 and 3, in a manner fully described in my aforesaid patent. The corrugated metal plates G are arranged to support a concrete bed, H, rising above the corrugations for deadening the floor, the concrete being filled in between and upon the plates G even with the top of the transverse beams B, thus forming a true and even bed, upon which the floor-boards will rest solidly throughout. The lath-suspender I is cut out near its ends at the upper edge to fit over and upon the lower flanges of the beams A, and thus be suspended by said flanges. Each end of the suspender extends beyond the beams A for riveting to the end of the adjoining suspender. They are perforated throughout their length near their lower edges, beneath the flanges of the beams A for the reception of the hollow metallic laths J, arranged at such distances apart as to form a lattice-support for a concrete bed, K, filled in upon the top of the laths so as to present a rough and jagged surface beneath, to which, in connection with the hollow laths, the plastering L will firmly key. The solid bed of concrete, plastering, and metallic laths are therefore arranged below the lower flanges of the floor-beams, with the concrete extending above the laths, thus intervening a solid bed between the ceiling and the flanges of the floor-beams, by which the ceiling is suspended, which affords a perfect protection to the said flanges against the action of fire. The lath-suspenders I, being supported near each end upon the floor-beams A, are liable to sag

between the beams; and to prevent this we arrange between the beams A suspending and bracing strips N, at as frequent intervals as necessary, being riveted by one end to the lath-suspending plates I, and extending up between the transverse plates B, to which they are also secured, as shown in Fig. 1 of the drawing.

This mode of fireproofing floors and ceilings obviates the necessity of the great weight incurred where brick arches are used, thus permitting the use of a lighter construction throughout the entire building; moreover, there being no lateral thrusts in any direction, tie-rods are unnecessary. The corrugated plates, being firmly riveted to the flanges of the transverse beams, thoroughly bridge the floor in every direction.

Having described our invention, we claim—

1. In fire-proof floors and ceilings having flanged floor-beams and transverse locking-plates, B, the combination therewith of the lugs M as a means for securing these parts together, essentially as described.
2. The entire ceiling, with its metallic laths J, concrete bed K, and plastering L, suspended directly by and upon the horizontal flanges of the floor-beams, as described.
3. The entire ceiling, with its laths J, concrete bed K, and plastering L, arranged beneath the flanges of the floor-beams, as and for the purpose described.

ISAAC HODGSON.

WILLIAM H. BROWN.
